The ornamental design for a tracked stroller frame device, as shown and described.

DESCRIPTION

FIG. 1 is an isometric perspective view of a tracked stroller frame device;

FIG. 2 is a top plan view thereof;

FIG. 3 is a bottom plan view thereof;

FIG. 4 is a rear perspective view thereof;

FIG. 5 is a front perspective view thereof;

FIG. 6 is a left side elevation view thereof;

FIG. 7 is a right side elevation view thereof; and,

FIG. 8 is a rear isometric perspective view thereof.
